UNITED STATES PATENT OFFICE.

ST. PAUL JOHNS, OF PITTSBURGH, PENNSYLVANIA, ASSIGNOR OF ONE-HALF TO
WILLARD E. KENNEDY, OF PITTSBURGH, PENNSYLVANIA.

METHOD FOR MAKING OVERLAYS FOR PRODUCING HALF-TONE CUTS.

No Drawing.

Application filed May 10, 1922. Serial No. 559,961.

To all whom it may concern:

Be it known that I, ST. PAUL JOHNS, a citizen of the United States, and a resident of Pittsburgh, in the county of Allegheny and State of Pennsylvania, have invented 5 certain new and useful Improvements in Methods for Making Overlays for Producing Half-Tone Cuts, of which the following is a specification.

10 This invention relates to a method for making overlays for producing or printing half-tone cuts.

15 The purpose of the invention is to provide means whereby an overlay may be produced in a short interval of time at a relatively low cost and said overlay being adapted to produce half-tone cuts of an exceedingly good quality.

20 The method of producing an overlay consists in taking a freshly inked proof and dusting the same with a particular kind of powder. Any particles of powder clinging to the proof is removed and the proof is then heated. Immediately after heating 25 the proof is dipped in a particular liquid and the same is then complete and ready for printing half-tone cuts.

30 The particular powder to be used should consist in 2 parts of 00 fine emery dust and 1 part of finely powdered rosin. These two substances should be thoroughly mixed.

The liquid should consist of one part of silicate of soda and three parts of water.

35 In preparing an overlay a proof may be pulled and well inked, that is inked sufficiently to bring out the solids in a decided black and without blurring the high lights. The proof may be pulled on book paper, preferably on the 60 lb. book paper.

40 The powder may now be dusted over the wet proof and then all surplus powder should be dislodged by slightly shaking the proof. The high lights may now be brushed out and the medium tones partly brushed.

45 Any ordinary camel hair brush will be suitable for this purpose. The proof is now heated preferably on its side opposite to that which has been powdered. Any convenient means may be utilized for heating 50 the proof.

The proof after being treated as above described is now quickly dipped in the liquid consisting of silicate of soda and water and then permitted to dry a minute

or two. It has been found by experience 55 that an overlay prepared in this manner can be completed in about five minutes.

The overlay is now used for printing half-tone cuts and this is carried out in a manner well known by those skilled in the 60 art.

It may be here mentioned that by using a powder of the character described the same adheres to solids where the heaviest overlay is needed. Little powder adheres to 65 the medium tones in the proof and the high lights are left bare of the powder. By the use of a brush the high lights may be brushed out and by lightly brushing the medium tones of the proof removes any 70 surplus powder that may not have been shaken off.

It is also important to point out that the action of the heat on the powder causes the rosin to melt and slightly raise on the 75 surface and thus fixes the emery powder on the places where it is needed to bring out the impression.

The solution of silicate of soda and water is merely to serve to ensure that the powder 80 fixed by the heat action on the overlay paper is of a permanent nature so that it will not give way or wear loose during long printing runs. In other words, the solution dries quickly and ensures the permanency of the overlay.

What I claim is:

1. The method of producing an overlay of the character described which consists in taking an inked proof, powdering the same 90 then heating the proof a predetermined interval and then dipping the proof in a solution of silicate of soda and water a predetermined interval and then allowing the proof to dry. 95

2. The method of preparing an overlay of the character described which consists in taking an inked proof and powdering the same with a powder consisting of emery dust and rosin, then heating the proof and 100 then dipping the proof in a liquid solution of silicate of soda and water a predetermined interval and then permitting the proof to dry.

3. The method of preparing an overlay 105 of the character described which consists in taking an inked proof, powdering the same with a powder adapted to intimately

combine with the ink upon said proof, then heating the proof a predetermined interval, then dipping the proof in a solution adapted to further set the ink and powder and then permitting the proof to dry.

4. The method of preparing an overlay of the character described which consists in taking an inked proof, powdering the same with a powder adapted to intimately combine with ink, heating the proof upon its unpowdered side, then dipping the proof in a solution adapted to further set the

ink and powder and then permitting the proof to dry.

5. The method of preparing an overlay of the character described, which consists in taking an inked proof, powdering the same with powder adapted to intimately combine with ink upon said proof, then dipping the proof in a solution adapted to further set the ink and powder, and then permitting the proof to dry.

ST. PAUL JOHNS.
